Primary Examiner — Elizabeth J Oswecki

(57) CLAIM

The ornamental design for a mask, as shown and described.

DESCRIPTION

FIG. 1 is a front view of a mask showing my new design;
FIG. 2 is a rear view thereof;

FIG. 3 is a left side view thereof;

FIG. 4 is a right side view thereof;

FIG. 5 is a top plan view thereof; and,

FIG. 6 is a bottom plan view thereof.

The broken lines in the figures illustrate portions of the mask that form no part of the claimed design.

1 Claim, 6 Drawing Sheets
